UNITED STATES PATENT OFFICE.

ALEXANDER CONSTANTINE IONIDES, JR., OF LONDON, ENGLAND.

AIR OR OTHER GASEOUS-FLUID HEATING FURNACE.

Application filed March 19, 1923. Serial No. 626,190.

To all whom it may concern:

Be it known that I, ALEXANDER CONSTANTINE IONIDES, Jr., a subject of the King of Great Britain and Ireland, and residing at 534 Porchester Terrace, London, W. 2, England, have invented certain new and useful Improvements in or Relating to Air or Other Gaseous-Fluid Heating Furnaces, of which the following is a specification.

10 This invention relates to the transmission of heat to a moving fluid in apparatus of the type consuming a combustible gaseous mixture of two constituents say, for example, gas and air correctly proportioned at constantly related pressures above that of the atmosphere for complete combustion in a chamber to which only the controlled gaseous fluids are admitted, and from which the products of combustion are expelled without being drawn or sucked by a reduced pressure such as results from a chimney or equivalent device.

In apparatus for transmitting heat from one to another of two fluids which are separated by a heat transmitting partition or wall, it is desirable that the counterflow system or movement of the two fluids in opposite directions be adopted, and if the movement of the fluid which is being heated can be effected as the result of the heat imparted thereto, the apparatus is correspondingly simplified. Such an arrangement calls for an upward movement of the fluid which is being heated and consequent downward movement of the heating medium, together with more or less upright partitions, but if considerable bodies of upwardly and downwardly moving fluids are to flow at a suitable speed over upright partitions, the 40 height of the apparatus is liable to become objectionably extended.

The object of the present invention is to overcome such difficulties and provide compact apparatus for satisfactorily heating considerable quantities of gaseous fluid.

The invention consists in the improved construction, arrangement and combination of parts hereinafter fully described and afterwards specifically pointed out in the appended claims.

Referring now to the accompanying drawings:

Figure 1 is a plan view partly in section of apparatus in accordance with the invention, and

Figure 2 is a side view of the heating device, one half shown in section and the other in elevation.

In the arrangement shown by way of example in the drawings, a combustion chamber *a* formed of a metal shell *a'* lined with refractory material *a''* is provided with a cover *a'''* and is carried upon a conduit structure or heat transmitting appliance as hereinafter described.

The combustion chamber *a* has suitable metal sockets *b* connected thereto, said sockets being adapted to receive burners *c*, say of the type described in my United States Patent No. 1,419,054 of June 6th, 1922, and comprising a chamber *c'* provided with a longitudinally adjustable tubular member *c''*, wherein is a third adjustable member *c'''*, the chamber *c'* having an orifice *c''''* and tubular member *c''* having an orifice *c'''''* in both disc-shaped ends of said elements closely adjacent to the combustion chamber so that the relative proportions of the two constituents of a combustible mixture may be adjusted close to the combustion zone. The mixture is admitted to the combustion chamber through a refractory channel or port *a''''* which is enlarged, as shown at *a'''''*, prior to its entry into the combustion chamber.

The burners *c* at the end remote from the combustion zone are each fitted with two boxes *c''''* and *c'''''*, to which constituents of a combustible mixture, for example gas and air, are supplied through pipes *d*, *d''* from a pressure balancing device *d''''* say in the manner described in my United States Patent No. 1,347,955 of July 27th, 1920.

The conduit structure or heat transmitting appliance *e* is formed of a series of superimposed hollow cylindrical or like elements, and consists in the embodiment illustrated of three tubular elements *e'* formed of say 9-inch lengths of 4-inch gas tube threaded at each end and screwed into flanges *e''*, *e'''*. The flange *e'''* may be of any ordinary type adapted to form a seating or base for the conduit structure, and the flanges *e''* are, as shown in the drawing, provided with recesses *e''''* for the reception of disc elements *e'''''* which are fastened together by flanges *e''''* and form cylindrical or disc-like elements of a diameter many times exceeding their length and alternating in the structure with the tubular elements *e'*.

It will be evident that flanges such as

e^2 , e^2 can be cast in one with the disc parts e^6 provided a pattern for the latter has movable pieces corresponding to e_2 , e_2 .

Within the large diameter disc-like elements are central deflecting plates f which extend to within a short distance of the inner circumference of the disc-like elements and thus divide the interior of the disc-like elements into two circular flat conduit chambers g communicating with one another only round their outer edges at g' . The plates f are held in position by distance pieces h consisting of columns or struts with abutments attached by screw threads to the ends thereof so as to render the length readily adjustable.

For supporting the combustion chamber a upon the top of the conduit structure e , a flange e^7 is provided having a cylindrical extension e^8 which fits within the shell a' of the combustion chamber.

The combustion chamber and conduit structure are enclosed within a housing j which is supported upon a metal base ring or stand k of channel or trough-like cross-section and provided with four or any other convenient number of legs k' by which it is held above the ground level at a suitable distance for permitting the entry of the air which is to be heated.

The housing j consists of three rings or belts j' of plate material and two annular baffle plates j^2 extending inward from the housing to within a convenient distance of the tubular members e' . A supporting cover j^3 is also provided at the top of the housing and the whole is covered with a lagging j^4 of suitable non-conducting material to prevent radiation of heat from the apparatus.

The annular baffles j^2 are conveniently provided with registering bands j^5 around their perimeters for registering with the shell members j' , and distance pieces h' of a construction similar to the distance pieces h , but considerably longer as may be necessary, are conveniently employed for positioning the baffles and disc-like members in relation to one another.

When operating in accordance with this invention, a combustible gaseous mixture correctly proportioned for complete combustion in the burners c is consumed in the combustion chamber a , and in view of the pressure being in excess of the pressure of the atmosphere, the products of combustion are expelled downwards through the flat conduit passages of the disc-like members and through the tubular elements e' until they finally escape along a flue or the like m from which they are, in a cooled condition, discharged to the atmosphere at a point preferably below the level of the combustion chamber.

The air in the housing j is heated by contact with the disc-like members and combustion chamber and rising draws in a fresh

supply through the opening below the stand k , the air being directed by the baffles j^2 over the surfaces of the disc-like members and being gradually heated up during its journey in counter-flow to the products of combustion until it finally reaches the top of the apparatus where it passes into a distributing head of any known type and thence into suitable ducts communicating, say, with the various rooms of a dwelling or the like which is to be heated, or the appliance may be used for supplying heated air for any other purpose or for heating any other gaseous medium, the temperature of which is to be raised.

Having now described my invention, what I claim as new and desire to secure by Letters Patent is:—

1. An air or other gaseous fluid heating furnace having in combination a plurality of hollow flat chambers having opposite apertures in their two larger sides, a partition in each of said chambers between said apertures terminating shortly before reaching the perimeter of said larger sides, conduits connecting the apertures of the series of chambers with one another to form a column-like structure of alternating conduits and chambers, a combustion chamber connected to the upper aperture of the top flat chamber, an outlet flue connected to the lower aperture of the bottom flat chamber, a casing surrounding said column with space around the perimeter of said chambers, and centrally apertured baffle plates in said casing between said chambers leaving spaces around said conduits.

2. An air or other gaseous fluid heating furnace having in combination a plurality of hollow flat chambers having opposed apertures in their two larger sides, a partition in each of said chambers between said apertures terminating shortly before reaching the perimeter of said larger sides, conduits connecting the apertures of the series of chambers with one another to form a column-like structure of alternating conduits and chambers, a combustion chamber connected to the upper aperture of the top flat chamber, gas combustion appliances positioned in said combustion chamber, an outlet flue connected to the lower aperture of the bottom flat chamber, a casing surrounding said column with space around the perimeter of said chambers and centrally apertured baffle plates in said casing between said chambers leaving spaces around said conduits.

3. An air or other gaseous fluid heating furnace having in combination a plurality of hollow flat chambers having opposed apertures in their two larger sides, a partition in each of said chambers between said apertures terminating shortly before reaching the perimeter of said large sides, con-

- duits connecting the apertures of the series of chambers with one another to form a column-like structure of alternating conduits and chambers, a combustion chamber connected to the upper aperture of the top flat chamber, combustion nozzles in said combustion chamber, means for regulating a gas supply and an air supply closely adjacent to said nozzles, means for maintaining a constant relationship between the pressures of a supply of gas and a supply of air, an outlet flue connected to the lower aperture of the bottom flat chamber, a casing surrounding said column with space around the perimeter of said chambers and centrally apertured baffle plates in said casing between said chambers leaving spaces around said conduits.
4. An air or other gaseous fluid heating furnace having in combination a plurality of hollow flat chambers having opposed apertures in their two larger sides, a partition in each of said chambers between said apertures terminating shortly before reaching the perimeter of said larger sides, conduits connecting the apertures of the series of chambers with one another to form a column-like structure of alternating conduits and chambers, a combustion chamber connected to the upper aperture of the top flat chamber, burners in said combustion chamber having a tube with an orifice in a disc-like end thereof, an axially displaceable sleeve having a like end provided with an end aperture opposite to said orifice, an inner movable member adapted to coact with said aperture to regulate the passageway therethrough, an outlet flue connected to the lower aperture of the bottom flat chamber, a casing surrounding said column with space around the perimeter of said chambers and centrally apertured baffle plates in said casing between said chambers leaving spaces around said conduits.
5. An air or other gaseous fluid heating furnace having in combination a plurality of hollow flat chambers having opposed apertures in their two larger sides, a partition in each of said chambers between said apertures terminating shortly before reaching the perimeter of said larger sides, conduits connecting the apertures of the series of chambers with one another to form a column-like structure of alternating conduits and chambers, a combustion chamber connected to the upper aperture of the top flat chamber, burners in said combustion chamber provided with axially displaceable concentric sleeving members adapted to regulate the proportions of a gaseous mixture closely adjacent to the combustion region, an outlet flue connected to the lower

aperture of the bottom flat chamber, a casing surrounding said column with space around the perimeter of said chambers and centrally apertured baffle plates in said casing between said chambers leaving spaces around said conduits.
